UNITED STATES PATENT OFFICE.

DUNCAN A. McCONNELL, OF ARLINGTON, AND ROBERT WANDRAS, OF KEARNEY, NEW JERSEY.

FLUSHING-VALVE.

1,217,792.

Specification of Letters Patent.

Patented Feb. 27, 1917.

Application filed February 20, 1914. Serial No. 819,952.

To all whom it may concern:

Be it known that we, DUNCAN A. McCONNELL, a citizen of the United States, and resident of Arlington, in the county of Hudson and State of New Jersey, and ROBERT WANDRAS, a citizen of the United States, and resident of Kearney, in the county of Hudson and State of New Jersey, have invented certain new and useful Improvements in Flushing-Valves, of which the following is a specification.

This invention relates to certain improvements in flushing valves and more particularly to that type in which the main valve after having been opened will automatically close, but only after a predetermined time interval. This type of construction involves a liquid chamber having a restricted inlet communicating with the inlet of the main valve, and so connected with the main valve that the liquid is expelled from said chamber upon the opening of the main valve. The time interval required for the closing of the main valve is dependent upon the time required for the liquid to refill said chamber through the restricted inlet of the latter. Among the particular objects sought to be accomplished by our improved construction is to reduce to a minimum the number of separate parts of the valve, to simplify these parts and reduce the cost of manufacturing them.

Reference is to be had to the accompanying drawing forming a part of this specification, and in which like letters indicate like parts.

Figure 1 is a substantially central longitudinal section through our improved flushing valve, which here appears as closed or in normal position of inactivity.

Fig. 2 is a similar section with certain movable parts slightly displaced from their normal positions, after pressure is first applied to the actuating device.

Fig. 3 is a similar section with the main valve fully open.

In the specific form illustrated, we employ a metallic shell 6, or containing member, of any suitable form, and adapted to be rigidly connected in circuit to the supply and delivery pipes. One end may have an annular portion 7 of reduced diameter, for attachment to a supply pipe 4 and a nipple 8 at one side for attachment to an outlet or delivery pipe, not shown. Between the in-

let and outlet is a partition or flange 11 of annular form, preferably integral with the wall and dividing the shell into an upper compartment 13 in open communication with the outlet and a lower compartment 14, in open communication with the inlet.

A valve casing 15, having the general proximate form of a cylinder, projects into the end of the shell opposite to the inlet and is threaded externally at its outer end so as to serve also as a screw plug. Intermediate of its ends the valve casing 15 is provided with a shoulder 20 of annular form, adapted to seat upon the annular partition or flange 11, and form a water-tight fit and complete the separation of the chambers 13 and 14. Above the shoulder 20 openings 18 lead through the casing wall from the interior thereof to the upper compartment 13, while below the shoulder 20 are a number of openings 22 communicating with the lower compartment 14. The lower portion 21 of the valve casing is of greater internal diameter than the main body portion thereof and forms a valve chamber 33 terminating at its upper end in an internal annular shoulder or seat 23 between the two series of the openings.

A closure plug 24 closes the lower end of the valve chamber 21, and is provided with a boss 26, preferably non-circular in cross-section to facilitate the use of a wrench in securing the closure in place. Through the closure and boss is a constricted passage controlled by a needle valve 27, adapted to seat against a frusto-conical terminal portion of the passage. A passage 28 extends through the valve and terminates below the seat. By turning the needle valve 27, it may be adjusted so as to regulate the flow into the valve chamber 33.

Within the valve chamber 21 is the main valve member 38, having the general form of an inverted cup with a cylindrical peripheral wall closely fitting within the cylindrical wall portion 21, and having an end wall adapted to engage at its periphery with the seat 23 and separate the chamber 33 from the interior of the valve casing above the seat 23. The peripheral wall is of such length that when the valve is seated as indicated in Fig. 1, the openings 22 will be covered by this peripheral wall, but when the valve is depressed to its lowermost position as indicated in Fig. 3, the entire wall

- will come below the openings 22. The valve member has a tubular stem 37 extending up through the top or end wall of the valve casing where leakage may be prevented in any suitable manner as for instance by an annular packing 34. A passage 39 extends from the valve chamber 33 through the valve 38 at the base of the valve stem 37, and is controlled by a valve member 41. 5
- 10 This latter valve has a valve stem 42, of smaller diameter than the tubular valve stem 37, and extending axially therethrough, to a knob 45 beyond the outer end of the tubular valve stem.
- 15 A spiral spring 43 acts to normally hold the valve 41 to its seat but the tension of the spring is not so great but that the valve 41 will always open before the valve 38, as hereinafter pointed out. As shown this 20 spring encircles the upper end of the valve stem 42, and is housed within a compartment 44 in the upper end of the valve stem 37. The knob preferably has an annular flange telescoping with the housing so as to 25 keep the spring concealed at all times, and the lengths of the two valve stems are such that the spring can be compressed to only a light extent before the knob engages with the valve stem 37.
- 30 With the various movable parts in their normal positions as shown in Fig. 1, no water can pass through or by the main valve. The valve chamber 33 will be filled by water entering past the needle valve and the valve 35 member 38 will be held against its seat 23 by the water pressure. The valve member 41 will be held against its seat by action of the spring 43.
- 30 When it is desired to open the valve, pressure is applied to the knob 45. As it moves 40 downwardly a very slight distance, the valve member 41 is displaced from its seat, as indicated in Fig. 2, and the water is allowed to escape from the chamber 33. The main 45 valve will then be moved to the lower limit of its travel, by the engagement of the knob with the valve stem 37, and will at the same time eject the water from chamber 33. The openings 22 are now uncovered and 50 water may flow freely inward through these openings, and follow the course indicated by the arrows in Fig. 3. Upon releasing the knob 45 the spring 43 instantly raises the knob 45 a slight distance relatively to the tubular valve stem 37 so that the valve 55 member 41 seats and prevents the further flow of water through the valve member 38 or through the chamber 33. The water entering slowly through the needle valve 27, 60 gradually raises the valve member 38 to its uppermost position, and after a predetermined time interval, closes the openings 22 so as to shut off the flow of water through these openings. Even after the closure of 65 these openings, the valve member 38 con-

tinues to rise until it seats against the shoulder 23 so that the flow is prevented not only by the closing of the openings 22 by the valve member 38, but also by the valve member pressing upwardly against its frusto-conical seat. Leakage is thus very effectively prevented, particularly as the valve member 38 must overlap the openings 22 for a little distance before the valve member reaches its seat. 75

The interval during which water flows freely through the openings 22 controls the volume of water discharged with each successive use of the flushing valve, and this interval is time-controlled to the extent that, 80 for a given pressure of water and a given capacity for the needle valve 27, a definite time interval is required for sufficient water to pass through the needle valve and raise the valve member 38 to the upper limit of its 85 travel.

In case it is desired to repair or replace any of the parts it is merely necessary to remove the valve casing 15, by unscrewing it from the shell 6, and lifting it out of the latter. The valve casing 15 carries both of the valve members 38 and 41, as well as all other movable parts so that they may be removed and replaced as a single 95 unit and without disturbing the adjustment or relative arrangement of any of the parts, and without detaching the shell from the supply and delivery pipes. The mere attachment of the casing clamps the shoulder 20 against the annular partition 11, and forms a thoroughly water-tight joint. The valve casing and shell may be 100 quickly and inexpensively manufactured by a very few operations on a turret lathe, as all of the finished surfaces are concentric. 105

We do not limit ourselves to the precise construction shown, as variations may be made therein without departing from the spirit of our invention, the scope of which is commensurate with our claim. 110

Having thus described our invention, what we claim as new and desire to protect by Letters Patent, is:

A valve casing and a main valve co-operating to form a pressure chamber in permanently open but restricted communication with the source of liquid under pressure, said casing having a main port out of communication with said chamber and normally closed by said valve, said valve being held closed by the pressure of liquid in said chamber, a tubular valve stem having an inlet communicating with said chamber and having an outlet on the low pressure side of the valve, a second valve seated at the inlet of said valve stem to normally prevent the escape of liquid from said chamber through said valve stem, and a second valve stem connected to said second mentioned valve and operating through said tubular valve 115 120 125 130

stem to open said second valve, and a spring within said tubular valve stem for normally holding said second valve closed and means for opening said first valve by a further end-
wise movement of the second valve stem after the opening of the second valve.

Signed at Newark in the county of Essex

and State of New Jersey this seventeenth day of February, A. D. 1914.
